BOTTLE

John C. Coons, Covington, Ky., assignor to The Clorox Company, Oakland, Calif., a corporation of Ohio

Filed Dec. 4, 1967, Ser. No. 9,627

Term of patent 14 years

(Cl. D9—44)

FIG. 1

FIG. 2

FIG. 3

FIG. 4

FIG. 5

FIG. 6

FIG. 1 is an elevational view of a bottle showing my new design.

FIG. 2 is an elevational view of the same as seen from the left of FIG. 1.

FIG. 3 is an elevational view of the same as seen from the right of FIG. 1.

FIG. 4 is an elevational view of the same with the bottle rotated 45° to the left from the view of FIG. 3.

FIG. 5 is a top plan view of the same; and

FIG. 6 is a cross sectional view of the same, taken on the line 6—6 of FIG. 1.

I claim:

The ornamental design for a bottle, as shown.
